UNITED STATES PATENT OFFICE.

GREGOR MELIKOV, OF CHICAGO, ILLINOIS, ASSIGNOR TO NATIONAL ADVERTISING CONTEST CO., A CORPORATION OF ILLINOIS.

DESIGN FOR AN ADVERTISING-CONTEST CARD.

Application filed September 21, 1925. Serial No. 14,837. Term of patent 14 years.

To all whom it may concern:

Be it known that I, GREGOR MELIKOV, a citizen of Armenia, residing at Chicago, in the county of Cook and State of Illinois, have invented a new, original, and ornamental Design for Advertising-Contest Cards, of which the following is a specification, reference being had to the accompanying drawing, forming part hereof.

The figure is a perspective view of an advertising contest card showing my new design.

I claim:

The ornamental design for an advertising contest card, as shown.

In testimony whereof I affix my signature.

GREGOR MELIKOV.
